METHOD OF MEASURING AND PACKING
PRESS ARTICLES AND PRESS ATTACH-
MENT USED THEREINWilliam Ross Smith, Portland, Oreg., assignor to
American Can Company, New York, N. Y., a
corporation of New Jersey

Application March 17, 1934, Serial No. 716,200

11 Claims. (Cl. 226—14)

The present invention relates to stacking, measuring and packing articles such as are produced in a press or other forming apparatus and has particular reference to a method of 5 packaging these articles in stack formation as received directly from the press and also to an attachment for a press which carries out some of the steps of the method by receiving the articles as they come from the dies of the press and 10 by stacking them within a removable magazine unit, a given measured charge being segregated from the supply of articles and the magazine unit with its charge being then removed and packed in a carton or other shipping container, 15 the magazine unit holding the charge in fully stacked condition until it is fully inserted in the carton after which the magazine unit is withdrawn and the filled carton sealed.

An object of the present invention is the 20 method of packing a stack, containing a predetermined number of articles, within a shipping package or container which comprises retaining the articles in stack formation as they are produced in a press and cutting off a given predetermined quantity, then holding the segregated 25 charge for insertion into a shipping package which is sealed after the stack of articles is in place and the holding device has been removed.

Another object of the invention is the provision 30 of an attachment for a press for receiving articles from the dies of the press and for packing a measured quantity within a removable magazine unit.

A further object of the invention is the provision 35 of an attachment for a press which holds a magazine unit in receiving position within the press so that articles as produced in the press are stacked within the unit and which segregates a measured predetermined quantity of articles 40 from the supply in a form within the magazine unit for packing in a shipping case or the like.

Yet another object of the invention is the provision 45 of a magazine unit holding and filling attachment for a press which is operated by the articles passing through the dies of the press so that a magazine unit gradually fills, features of the device insuring a measuring of the number of articles for the magazine unit, to the end that a predetermined measured charge of stacked 50 articles may be enclosed within a suitable package or container.

A still further object is the provision of automatic press stopping devices in a machine of the character described which provide against an 55 excessive fill of articles first within the magazine

unit and thence within a carton or other kind of container.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a packaging device utilizing certain steps of the present method invention and disclosing a magazine unit in position within a press and filled with a charge of articles, the view illustrating the measuring of the unit charge prior to its removal and 15 packing;

Fig. 2 is a view similar to Fig. 1 illustrating the stacking and measuring attachment with the magazine unit removed;

Fig. 3 is a perspective view of the magazine unit filled with a measured charge of articles; 20

Fig. 4 is a perspective view of a packing or shipping container showing it with the filled magazine unit inserted;

Fig. 5 illustrates the same in inverted position 25 and showing the partial removal of the magazine unit;

Fig. 6 is a perspective view of the sealed pack- 30 age or shipping container with its enclosed measured charge of articles;

Fig. 7 is a perspective view similar to Fig. 2 illustrating a magazine unit in inserted position and ready to receive a supply of articles;

Fig. 8 is a face view of one form of blank or other stock material suitable for cutting in a 35 press from which one form of article is produced;

Fig. 9 is a plan view of such an article after being blanked in the press;

Fig. 10 is a sectional view of the stacking and measuring attachment illustrating its relation 40 to the press and showing a magazine unit in inserted position ready to receive articles from the press;

Figs. 11 and 12 are cross sectional views taken substantially along the line 11—11 and along the 45 broken line 12—12 both in Fig. 10; and

Fig. 13 is a longitudinal sectional view taken along the runway of the stacking and measuring attachment as viewed substantially along the line 13—13 in Fig. 7 and illustrating in 50 addition the blanking dies of the press, parts being broken away and some of the articles within the magazine having been removed.

The drawings disclose briefly the various steps of the instant method invention and also show 55

more in detail the press attachment by means of which the most critical features of the invention are consummated. In the disclosure in the drawings a flat blank A is shown (Fig. 8) as being representative of a common form of material as used in the canning industry and from this the flat form, shape or disc B (Fig. 9) may be blanked out in the press. Such a shape has been selected as illustrative of a suitable article for packing in a shipping container C (Figs. 4 and 5) such article shapes being produced in great quantities.

In the instant invention the articles B are blanked in the dies of the press and these stack up one by one preferably in the top of an inclined runway. Into this runway a holding device such as a magazine unit may be inserted at the bottom and the articles fill up in the unit from the top at the same time moving a stack retaining member down until the articles reach to the bottom of the magazine.

A predetermined quantity of articles is now segregated from the stack and only a measured charge of articles in the magazine unit remains in the unit as it is withdrawn from the press and replaced by an empty unit. The articles still left in the runway are held there, this removal of a filled magazine and its replacement by an empty one being done without stopping the operation of the press or the progressive addition of articles to the top part of the stack within the runways.

The filled magazine unit makes a convenient unit article to handle and with its measured charge is inserted preferably from the bottom into a shipping container or carton closed at one end as shown in Fig. 4. This package is now inverted and the magazine unit is withdrawn (Fig. 5) leaving the articles still in stack form within the carton. This filled carton need only be closed at its now top or open end to produce the finished package D (Fig. 6) containing the desired quantity of articles which may then be shipped or disposed of as desired.

The press and the stacking and measuring attachment for receiving the discs B will now be considered in detail.

The press comprises a frame 21 (Fig. 1) having a bolster plate 22 (Fig. 13) formed as an integral part of the frame. A lower die block 23 may be mounted upon the bolster plate 22 and secured in any suitable manner, this block holding a blanking die 24 which cooperates with the usual punch 25, the parts 24, 25 being illustrative of working elements of press dies.

The usual opening through the die 24 (Fig. 13) provides a passageway for the discs B as they come from the die elements and these, after leaving the die opening, press into an inclined runway 26. Runway 26 may be formed by side bars or rails 27, a top bar 28 and a bottom bar 29, all of these bars being held together at their upper or press ends within a collar 31 bolted to the bolster plate 22.

The top bar 28 extends only a relatively short distance below the collar 31 and the runway below the end of this bar is open along its top side as well as being open at its lower end. The side bars 27 and the bottom bar 29 (Figs. 2 and 13) beyond the end of the bar 28 are held together by an end yoke 34 and an intermediate yoke 35.

A support bar 36 (Figs. 1 and 10) is also mounted in the press and extends parallel to and to one side of the runway 26. The upper end

of this bar is bolted to the collar 31 and its lower end is connected to a bracket 37 which in turn is secured to a cross bar 38 which extends between parts of and is bolted to the frame 21 of the press. The bracket 37 is also connected to the end yoke 34 as at 39.

A magazine unit is provided for receiving the articles and permitting easy measuring and subsequent handling for packing and this unit is preferably formed by four parallel spaced rods 41 (Fig. 3) secured to a bottom block 42. This magazine unit is adapted for insertion into the lower open end of the runway 26, the two lower rods 41 in their inserted position being supported upon seats 43 formed in the U-shaped brackets 34, 35 and in a channel iron 46 extending between the brackets. The magazine unit is now in position within the press runway 26 so that the articles B passing down between the side bars 27 of the runway also pass in between the rods of and into the magazine unit.

Provision is made for holding the magazine unit in its inserted position and for this purpose there is provided a clamping lever 48 (Figs. 2, 7 and 11) which is pivoted on a pin 50 held in a bracket 51. This bracket may be an integral part with a slide 52. The support bar 36 is preferably grooved along both sides to form channels 53 and the slide 52 is suspended on and moves beneath the support bar 36, portions of the slide extending up into the channels 53.

The slide 52 during the filling of the magazine remains stationary and when each magazine unit is inserted in the press this slide is located in its uppermost position, that is, with its upper end against a stop pin 54 (Fig. 7) carried in and extending down from the support bar 36. In this located position the lever 48 is in a position just beneath the bottom block 42 of the magazine unit and as it is brought into its horizontal clamping position (Fig. 11) a projection 55 of the lever engages below the bottom of the magazine unit and holds it in place.

The lever 48 is formed with an operating handle 56 by means of which it may be easily moved from the open or unclamped position of Fig. 2 into the horizontal clamping position of Figs. 7 and 11. The clamping action as it is effected by the lever and which frictionally holds the slide 52 in its located position against the stop pin 54 will next be considered.

The slide 52 (Fig. 11) carries a pin 57 supported in lugs projecting down from the slide body on one side. A lever 58 has one end pivotally mounted on the pin 57 and its opposite end 59 extends beneath the pin 50 which connects the lever with the slide. Slide 52 is formed with an aperture 60 and a clamping pad 61 of suitable resilient and frictional material such as rubber is carried in a holder 62 which is located within the opening 60.

During the positioning of the slide 52 against its stop pin 54 and while the lever 48 is in raised non-clamping position, the slide is free to move on the support bar 36. At such a time the lever 48 holds the pad 61 out of clamping engagement with the bottom of the support bar. For this purpose the lever 48 is formed with a projection 63 and when the lever is in its raised position this projection presses down on an insert plate 64 carried in the end 59 of the lever 58 and holds down the engaged end of this lever.

A spring 65 is located on a pin 66 which is carried in the slide 52 and which projects down through an opening in the lever 58 adjacent the 75

plate 64. A washer with a nut 67 threadedly engaged on the pin 66 holds the spring 65 so that its upper end presses against the lever 58. As soon as the lever 48 is brought down into clamping position and in holding engagement with the bottom block 42 of the magazine unit, its projection 63 is moved up and out of engagement with the insert plate 64. This is the position shown in Fig. 11.

10 The spring 65 being now unrestricted forces up on the free end 59 of the lever 58 and this moves the pad 61 into clamping engagement with the lower face of the support bar 36. This yieldingly holds the slide 52 at a given position on the support bar and at the same time retains the lever 48 in position and through it the magazine unit which is thus held in its inserted position. The articles B passing down within the runway 26 now move in between the bars 41 of the magazine unit 20 coming into stack position within the magazine.

15 During this filling of articles in the magazine unit the bottom of the stack is yieldingly held by a slide unit also carried on the support bar 36. As each article is added to the upper end of the 25 stack such a slide unit moves down with the entire stack a distance sufficient to accommodate the new addition.

20 This slide unit comprises a slide 69 (Figs. 1 and 12) which is mounted to slide upon the support bar 36 being formed with lower slide projections which extend into and move along the channels 53 of the support bar. The channels 53 are wide enough to accommodate the slide projections of both slides 52 and 69 and these lower and upper 35 slide projections do not interfere with one another so that there is no interference between the two slides and one slide can therefore move adjacent the other.

25 The slide 69 is extended laterally on one side and vertically into a slide frame 70 which is located over the runway 26 and at the time the articles begin to pass into the inserted magazine unit this frame is over the upper end of the magazine unit. A vertically movable blade 71 is slidably mounted in the frame 70 and carries at its 40 upper end a handle 72. The lower end of the blade 71 is sharpened or beveled at 73 and this end at such a time extends down in the path of the articles B within the runway 26 and supports the lower end of the stack of articles.

30 The slide 69 carries a bell crank lever 75 which is pivotally connected on a pin 76 carried in lugs formed in the slide on the side opposite to the blade 71. This bell crank lever pivotally supports a clamping holder 77 which is suspended on a pin 78 carried in the lever. The holder 77 is located in an opening 79 formed in the slide 69 and carries a clamping pad 80 which, like the pad 61 of the slide 52, is of suitable frictional material.

35 Pad 80 is normally held down against the upper surface of the support bar 36 under spring action. For this purpose the bell crank lever 75 extends beyond the pin 78 in a slotted end 81. A stud 82 is threadedly secured in the slide 69 and extends up and through the slotted end 81 of the bell crank lever 75. This lever end and stud support a spring 84 which is held confined by a washer and by a nut 85 threadedly engaging the stud.

40 Spring 84 pressing down on the lever end 81, as long as the bell crank lever is free to move, holds the clamp unit with its pad 80 in frictional engagement against the support bar 36. This clamping action is sufficient to retain the slide 69 in position against inadvertent move-

5 ment but is not strong enough to resist the constant downward pressure of the press as additional articles B are inserted into the top of the stack.

5 The slide 69 thus intermittently moves down a distance equal to the entire length of the magazine unit rods 41 until the blade 71 strikes against the bottom 42 of the unit. The striking position is shown in dotted lines in Fig. 13 at which time the magazine unit will be filled. The operator can 10 immediately perform the measuring operation or if he does not attend at once to the magazine and its charge, the magazine unit, the slide 69 and the slide 51 will simultaneously move down as the articles continue to fill in at the top of the 15 stack.

20 Provision is made for automatically stopping the press in the event that this downward movement continues beyond a point of safety. This may be done in a number of different ways, one such method being briefly indicated in Fig. 10. A rod 86 is pivotally connected at one end as at 87 to the slide 52 and extends at the other end through an arm 88 of an electric switch box 89 secured in the press frame 21. The rod 86 is 25 formed with a hooked end 90 and as the slide 52 moves down along the support bar 36, the rod 86 is pulled between spaced pins 91 carried in the switch arm 88.

30 As the limit of movement of the slide 52 is reached, the hooked end 90 of the rod engages the upper pin 91. Continued movement of the slide 52 from this position now shifts the switch arm 88 against the action of a spring 92 and this in turn stops the operation of the press or the 35 feeding of the blank A into its dies in any suitable manner.

35 To measure a charge of articles B now in the filled magazine unit, the operator grasps the handle 72 of the blade 71 and raises it until a 40 shoulder 93 formed on the blade strikes against the lower edge of the guideway frame 70. This raising of the blade not only removes it from its position at the bottom of the stack of articles B but also releases the spring clamp action on 45 the pad 80 resting against the top of the guideway bar 36 under the action of the spring 84.

40 An arm 94 (Figs. 1 and 12) is pivotally connected on a stud 95 carried in lugs 96 formed on the slide 69. This arm 94 is loosely connected 50 with the blade 71 by means of a pin 97, carried in the blade, which moves within a slotted end of the arm. The boss of the arm 94 which is mounted on the stud 95, is formed with a cam projection 98 and when the arm is lifted by the 55 raising of the blade 71 this cam projection strikes against a pin 99 carried on an arm 100 of the bell crank lever 75.

45 The pin 99 and the lever arm 100 are moved back, oscillating the bell crank lever on its pivotal support 76, against the action of the spring 84, lifting the holder 77 and its clamping pad 80 from clamping position on the support bar. This frees the slide 69 which may then be easily moved. With the blade 71 in raised position the slide 69 is 60 slid back or retracted along the support bar into a measuring position.

50 A chain 101 is secured at its upper end to the slide 69 and at its lower end to the slide 52. This chain limits the amount of distance the slide 69 65 can be separated above the slide 52 which, it will be recalled, is still at the bottom of the magazine unit irrespective of how far the unit and slide have moved. With the chain taut slide 69 is now adjacent the top of what will constitute 75

the measured charge of articles B in the magazine when the measuring operation is completed.

With the slide 69 in this position the blade 71 is forced down (Fig. 1) and its beveled edge 73 passes between and separates the articles B within the stack into two sections. This segregates a predetermined quantity of articles in the magazine unit from the rest of the stack of articles in the runway 26. At the same time lowering of the blade 71 carries the cam end 98 of the arm 94 out of holding position and allows the spring 84 to press the pad 80 against the support bar 36.

The handle 48 is now raised to unlock the magazine unit from its inserted position and the magazine with its charge of articles is then drawn out from the press while the blade 71 holds back the articles remaining in the press runway (Fig. 2). This magazine unit with its charge of articles is shown in detail in Fig. 3. This segregation of the articles and the withdrawal of a filled magazine constitutes a major feature of the instant invention. Each time the magazine is withdrawn from the press after such segregation there is the assurance that the charge of articles within the magazine is of a predetermined quantity.

A shipping container box, or carton C is now inverted over the top of the magazine. This carton may be of the form illustrated in Fig. 4 with its bottom end closed except for its corners which are open. In fully inserted position, the upper ends of the rods 41 of the magazine unit protrude through these corner openings and extend beyond the closed end of the box or carton. Carton C with its contained magazine and charge of articles is now turned over whereupon the magazine unit is withdrawn (Fig. 5) from the top leaving the charge of articles therein. A final sealing of the carton C may be had in any suitable manner as by folding in end flaps and sealing by a sticker 105 or otherwise. This completes the steps of the instant method and produces the unit package D presenting the appearance as shown in Fig. 6.

It should be observed that when an empty magazine unit is inserted into the runway 26 the slide 52 is always pushed back into position against the stop pin 54. This restores the switch arm 88 in the event that the slide 52 had been carried down beyond the safety point. Since the filling of articles B into the runway is taking place all of this time, except where the press has been stopped by the switch 89 in which event the press will resume operations as soon as the switch arm 88 is released, it may be that when a magazine unit is inserted the slide 69 has already moved down. In fact the upper position of this slide relative to the runway 26 varies, as where the operator has not immediately removed a filled magazine unit, but these conditions do not affect the correct measuring of a charge of articles. A new magazine may become filled immediately after it is inserted but the length of the chain 101, which remains constant, always determines the number of articles segregated from the runway stack.

It is thought that the invention and many of its attendant advantages will be understood from the foregoing description, and it will be apparent that various changes may be made in the form, construction, and arrangement of parts of the apparatus mentioned herein and in the steps and their order of accomplishment of the process described herein, without departing from the spirit and scope of the invention or sacrificing all of its material advantages, the apparatus and

process hereinbefore described being merely a preferred embodiment thereof.

I claim:

1. The method of measuring and packing non-circular articles in a uniform stack formation as received from a press, which consists in stacking the articles uniformly within a runway and thence to a magazine while holding the articles from individual rotation, segregating a predetermined quantity of articles from the stack while the press continues to operate and while the articles continue to stack to provide a measured charge of stacked articles within the magazine, moving said segregated quantity of articles bodily with said magazine and longitudinally of the runway by the pressure of succeeding non-segregated articles in the runway while preserving the segregated relation of such articles with respect to the remainder of the moving stack in the runway, whereby said magazine with its measured charge may be removed as a unit from the runway and inserted within a container to deposit the charge therein while holding the articles against individual relative rotation.

2. The method of measuring and packing articles in stack formation as received from a press, which consists in feeding the articles to a runway and thence to a magazine and stacking the articles therein as they come from the press, segregating and confining a predetermined quantity of the stacked articles within the magazine while the press continues to operate and while the articles continue to stack to provide a measured charge of stacked articles, separating said measured charge from the remaining articles in the stack while preserving its axial alignment with the latter, moving said measured charge bodily with said magazine relative to and longitudinally of the runway by the pressure of succeeding non-segregated articles in the runway while maintaining the separated relation of the charge with respect to the remainder of the moving stack in the runway, and holding the articles against individual rotation during stacking and removal, whereby said removed magazine containing a predetermined charge of the stacked articles may be filled as a unit into a receptacle.

3. In a stacking and measuring attachment for a press, the combination of a storage runway for receiving articles in stack formation as produced by the press, a magazine unit for holding said articles, means associated with said runway for holding said magazine unit in receiving position so that the articles pass from said runway into said magazine, and means also associated with said runway and movable into a position which is a given distance from the bottom of said magazine unit for measuring a predetermined quantity of articles in said magazine.

4. In a stacking and measuring attachment for a press, the combination of a storage runway for receiving articles in stack formation as produced by the press, a magazine unit for holding said articles, means associated with said runway for holding said magazine unit in receiving position within the press so that the articles pass from said runway into said magazine, means also associated with said runway and movable into a position which is a given distance from the bottom of said magazine unit for measuring a predetermined quantity of articles in said magazine, and devices associated with said measuring means for retaining the stack of articles in said runway while said filled magazine unit is removed and replaced by an empty magazine unit.

5. In a stacking and measuring attachment for a press, the combination of a storage runway for receiving articles in stack formation as produced by the press, a magazine unit for holding said articles, means associated with said runway for holding said magazine unit in receiving position so that the articles pass from said runway into said magazine, means also associated with said runway and movable into a position which is a given distance from the bottom of said magazine unit for measuring a predetermined quantity of articles in said magazine, and devices also associated with said runway for cutting out a predetermined quantity of articles from the stack in said runway and in said magazine so that the latter when removed contains only that predetermined quantity.

6. In a stacking and measuring attachment for a press, the combination of a storage runway for receiving articles in stack formation as produced by the press, a magazine unit for holding said articles, means associated with said runway for holding said magazine unit in receiving position in the press so that the articles pass from said runway into said magazine, a slideway located at one side of said held magazine, means also associated with said runway and movable in said slideway for measuring a predetermined quantity of articles in said magazine, and devices associated with said measuring means for cutting out the desired predetermined quantity of articles from the stack so that the magazine unit when removed contains only that measured quantity.

7. In a stacking and measuring attachment for a press, the combination of a magazine unit for holding the articles produced by the press, a storage runway for first receiving the articles in stacked formation as produced by the press said runway being also adapted to receive said magazine unit, a slideway located at one side of said held magazine, a slide movable on said slideway, means associated with said runway and carried by said slide for holding said magazine unit in inserted position in the press so that the articles pass from said runway into said magazine, a second slide also movable on said slideway and means associated with said runway and with said second slide for measuring and segregating a predetermined quantity of articles in said magazine.

8. In a stacking and measuring attachment for a press, the combination of a storage runway for receiving articles in stacked formation as produced by the press, a removable magazine unit adapted for insertion into one end of said storage runway and into receiving position so that the articles pass from said runway into said inserted magazine, the magazine thereupon functioning for holding said articles, a pair of

slides associated with said runway and movable parallel to the line of travel of the articles entering said magazine, and means associated with said runway and utilizing said slides for measuring and segregating a predetermined quantity of articles while in said magazine as a unit charge.

9. In a stacking and measuring attachment for a press, the combination of a storage runway for receiving articles in stack formation as produced by the press, a magazine unit for holding said articles, means associated with said runway for holding said magazine unit in receiving position, means for retaining said articles in stack form while at the same time moving in synchronism with the operations of the press so that the articles pass from said runway into said magazine, means associated with said magazine holding and said stack retaining means for measuring and segregating a predetermined quantity of articles in said magazine, and means for clamping said stack retaining means in operating position while said magazine is removed with its segregated articles.

10. In a stacking and measuring attachment for a press, the combination of a magazine unit for holding the articles produced by the press, a storage runway for first receiving the articles in stack formation as produced by the press, said runway being also adapted to receive said magazine unit, means associated with said runway for holding said magazine unit in inserted position in the press so that the articles pass from said runway into said magazine, said magazine unit holding means yielding to permit movement of said magazine unit after accumulation of a given number of articles in said unit, and means for stopping the feeding of articles into said runway when articles accumulate in said magazine beyond a certain quantity.

11. The method of measuring and packing non-circular sheet metal articles in stacked arrangement as they are punched, which consists in punching the articles, guiding the articles into stacked arrangement within a runway and thence to a magazine while holding the articles from individual rotation, thereby giving corresponding and uniform alignment in the runway and magazine to the non-circular parts of said articles constituting the stack, segregating a predetermined quantity of said articles from the remainder of the moving stack, and bodily moving said segregated quantity of articles while in said magazine relative to the runway by the pressure of succeeding non-segregated articles in the runway and longitudinally of the moving stack therein while maintaining their separated relation with respect to the latter.

WILLIAM ROSS SMITH.
